Primary Examiner — Llorellys Martinez(74) *Attorney, Agent, or Firm* — Foley Hoag LLP; Peter A. Sullivan; Stephen J. Kenny(57) **CLAIM**

The ornamental design for an article of jewelry, as shown and described.

DESCRIPTION

FIG. 1 is a front view of the article of jewelry showing my new design.

FIG. 2 is a back view thereof.

FIG. 3 is a perspective view thereof.

FIG. 4 is a bottom view thereof.

FIG. 5 is a top view thereof.

FIG. 6 is a right view thereof; and,

FIG. 7 is a left view thereof.

The broken lines shown in the drawings represent portions of the article of jewelry which form no part of the claimed design.

1 Claim, 7 Drawing Sheets(56)
